Aram Gallig - Manufactured North Carolina

Sewing Machine

The subject referred to us from Sims, Peale and Company, one of the Slave-Owners
and dealers in the world of the Slave, is the Gallig himself of his invention
in the Cotton-Fields.

It will be plain that present shall come. But know that Aram Gallig of whom
we speak in the County of Hertford and State of North Carolina has invented a
most useful Improvement in the Cotton-Planter and that the following is a full and
detailed description of the construction and operation of the said Machine as invented in the
present time, showing mode of use 14 pounds to the bushel to calculate the operation of the
Cotton-Planter which is employed to use on a small power-horse or mule
the general difficulty presented by the disposition the seeds should adhere together
so that it will not be necessary to separate them the following mode of operation
which has been found fully to answer the purpose and may be adopted to the use
of any plough intended to be used with this.

The beam of the plough which is straight has the handles
attached to the side in such a manner that the ends of the leathes crossing as they
drawn backwards are kept at the proper distance apart by means of a small hole
paper through the top of an upright inserted into the back of the beam.

Secure this upright to the beam in the
and at such a distance below as will accord with that of the Cotton-Planter from
immediately behind the said upright placed the spear which consists of a proper
circular steel plate from the beam into which it is secured by a suitable iron
ring with to form a regular and projection towards the front. Having secured the
shape of the iron about the hole of the spear, the same is passed through the
projection, so as to form the regular projection up the ridge and of such a
width on either side of the ring as to end his wheel intended to regulate the operation
of the spear. Now is to be used where the ridge or bed is already prepared. Accordingly
as it is the track of the bed of the said bed this is prepared in 10 ft 10 upper edge
is prepared by hand and a horse substituted for the mule and 10 yards

the trouble of such a sowing as usual. In order to illustrate the seed I construct this following spade, consisting of a hopper box or on top of & between the handles just behind the spade & which is then secured to the handles the shape will be best adapted by using an oblong following the length of the beam.

To the bottom of the four sides (which are gradually to approach each other as they descend) is to be fitted a shield or slide board, so as to close up the opening when desired either entirely (as when in turning or in spots not to be drawn) or in part so as to let out but a given portion of seed such as may be required to the plough. This motion to be given to this slide board is produced by the following arrangement; a broad piece of leather which I find to answer well as any thing else is fastened to the bottom of the front side of the hoppers so as to allow the board to shake from side to side, under the opposite a back side of the hoppers another piece of leather is attached to the outer side of the slide board or a pin is put through it & the end of a long lever or handle consisting of a handle shaft sufficiently long to reach to the end of the plough handle so as to be grasped at the same time that with wheel desired. This shaft is supported beneath the beam, while kept the handles apart by means of a stopper or eye secured thereto and in which it plays from side to side.

Beneath this first hopper is intended to contain the seed is placed another including the lower part of it & descending by a gradual diminution of its width so as to leave below the beam, where the sides approach the rear a long narrow opening of about twelve inches in length and about one in breadth through which the seed passes into the trammel previously opened by the box or spade & a corresponding hole made through the beam by shaking the shaft handle or moving it from side to side as the plough advances the stopper forming the fulcrum regulates the distance to which the slide board can move from side to side the pin through it and the end of the shaft serving as a pivot and the leather being long sufficient to admit of the same moving. In this manner a long transverse opening is formed at each stroke or movement of the shaft and slide board on say the left hand side (as being the most likely) during the progress of the plough we should it be desired to turn or on other occasions the opening may be effectually closed so as to prevent the passage of the seed by passing the shaft to the plough handle of the opposite side & the transverse opening & retaining it there by the grasp of the hand worn leather until the following is to occur however that I claim as my invention and first previously known

... the above described machine is not the arrangement of the whole machine but only
that part of it which performs the operation of distributing the portions of seed intended to be
sown from the first hopper to the sowing machine consisting of the combination formed by
the slide board attached as described to the hopper and moved from side to side by the slide
suspended from the beam by the eye & working with the slide board by means of the pointer
spur. - Other the use of the second hopper below, connected with the hole through the beam.

These parts being combined upon the principle of regulating the casting by the hand at pleasure so as to distribute more or less or have the passage altogether as desired. In testimony that the stone is a full and clear description of the construction and principles adopted in the mode of operation I have hereunto set my hand this twenty fifth day of May eighteen hundred and thirty five
